CONTAINER FOR TOBACCO, CIGARETTES,
AND PIPE CLEANERS, AND THE LIKE ARTICLESNick Sevastopoulos, New York, N. Y., assignor to
Eleftheria Sevastopoulos, New York, N. Y.

Application October 9, 1942, Serial No. 461,424

7 Claims. (Cl. 206—41)

This invention relates to smoker's packages. It is particularly directed to containers for tobacco, cigarettes, and pipe cleaners, and the like articles.

An object of this invention is to provide a smoker's package adapted to contain a small supply of tobacco and pipe cleaners, the arrangement being such that the package may be refilled with tobacco and pipe cleaners so that the person using the package may carry a day's supply compactly in the pocket, thus eliminating the necessity of carrying large packages of tobacco and pipe cleaners such as are sold in stores.

Another object of the present invention is to provide a container of the character described comprising an outer tube and an inner tube provided with a spout, and means for ejecting the inner tube so that tobacco may be easily poured therefrom into a pipe.

Still a further object of this invention is to provide a container adapted to carry a supply of tobacco or cigarettes, and means to facilitate removal of the tobacco or cigarettes from the package.

An object of this invention is to provide, a 25 smoker's package of the character described, comprising a container for tobacco, and a spout of flexible, normally stiff sheet material, attached to the container at one end, and being flexed over the mouth of the container with the free end of the spout engaging the container to hold the spout in position covering the mouth or open end of the container, means being provided to release the free end of the spout to permit said spout to snap into normal, straight condition, whereby said spout can be used to facilitate pouring of tobacco from the container.

Yet a further object of this invention is to provide a compact, neat and durable package of the character described which shall be relatively easy to manipulate and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is an axial, cross-sectional view of a smoker's package embodying the invention;

Fig. 2 is a front elevational view thereof, with the cover removed;

Fig. 3 is a partial, front elevational view with the spout opened up and the inner tube partially ejected;

Fig. 4 is an axial, cross-sectional view of the pouring end of the device, illustrating the method of pouring tobacco into a pipe;

Fig. 5 is a view similar to Fig. 1, but illustrating a modified construction;

Fig. 6 is an elevational, cross-sectional view of a smoker's package embodying the invention and illustrating another modified construction;

Fig. 7 is a side elevational view thereof, with the cover removed and one of the cigarette containers ejected;

Fig. 8 is a top plan view of the structure shown in Fig. 7;

Fig. 9 is an axial cross-sectional view of a smoker's package embodying the invention and illustrating still another modified construction;

Fig. 10 is a partial, front elevational view of the package shown in Fig. 9 with the cover removed; and

Fig. 11 is a view similar to Fig. 10 but showing the pouring spout snapped into position for use.

Referring now in detail to the drawings, and particularly to Figs. 1, 2, 3, and 4 thereof, 10 designates a smoker's package embodying the invention. The same comprises an outer tube 11 having a bottom wall 12 and a cylindrical wall 13.

The tube 11 may be made of card board, plastic material, metal or any other substance. 35 It is preferably open at the top. It is formed with a longitudinal slot 14 terminating short of the ends of the tube. The tube 11 may be covered by a wrapper 15 of paper or any other suitable material.

Telescoped within the tube 11 is an inner tube or container 16 made of card board, paper or any other suitable material preferably softer than the material of the outer tube. The inner tube 16 may also be open at the top and may 45 contain loose tobacco 17. It is preferably closed at the bottom and extends substantially the length of the outer tube. Frictionally receiving the lower end of tube 16 is a cup shaped member 20 having a handle or tab portion 21 extending through the wall 14. The handle 21 may be used to move the inner tube 16 upwardly out of the outer tube 11.

Attached to the open end of inner tube 16 is a pouring spout 23 made of celluloid or the like material which can be flexed but which will

spring into normal, straight or stiff position when pressure therefrom is removed. The spout 23 has one end 24 fixed to tube 16 as shown in the drawings. The outer end 24 of the spout may be flexed downwardly to cover the open end of the inner tube or container and is inserted into the slot 26 formed between the outer wrapper 15 and the upper end of cylindrical wall 13. If desired, the free end of the spout may be merely inserted within the outer tube.

Fitted over the upper end of the container is a cup shaped cover 30. When it is desired to use some of the tobacco from the package 10, the cover is first slipped off, and the handle 21 grasped and moved upwardly. When this is done the upper end of the inner tube 16 moves with the spout 23 to free the end 24 thereof, and as soon as that is done the spout will spring out into the straight or stiff shape shown in Figs. 3 and 4. The package can thus be tilted and the spout inserted into a pipe to facilitate pouring tobacco into the pipe from the inner container without loss of tobacco.

It will be noted that the length of the package 10 is greater than the length of usual pipe cleaners. Attached to the tube 11, and extending longitudinally thereof, is a secondary compartment 32 closed at its lower end 33 and adapted to contain several pipe cleaners 34. It will now be understood that the package 10 can be easily carried in the pocket and refilled from a can of tobacco each day. The inner tube 16 being frictionally fitted within the cup shaped member 20 may be removed therefrom to facilitate refilling.

In Fig. 5 there is shown a smoker's package 10a embodying the invention similar to the package 10 with the exception that the inner container 16a is divided by perforations 40 into sections. Within the inner tube 16a are a plurality of individual pipe refills 41, each containing enough tobacco to refill a pipe.

When the inner tube 16a is ejected one of the refills 41 may be broken off at the perforation 40, and the contents thereof inserted into the pipe.

Furthermore, spout 23a is attached to the outer tube instead of the inner tube. When the inner tube is ejected somewhat the spout is freed.

In Figs. 6, 7 and 8 there is shown a smoker's package 10b containing cigarettes 50. The package 10b comprises a flattened tube 51 open at both ends. Within tube 51 are a pair of similarly disposed cases 52 open at their outer ends and closed at their inner ends. Each case 52 is adapted to contain 5 cigarettes. The cigarettes extend beyond the open ends of the cases 52. Between the cases 52 is a sliding block 53. The sides of tube 51 are formed with slots 55, and attached to opposite ends of block 53 are pins or ears 56 passing through the slots 55 and formed with heads 57. Upon engaging the heads 57 the block 53 may be pushed up or down to eject one or the other of the cases 52. The opposite ends of tube 51 are opened but may be closed by frictionally fitted covers 60. The tube 51 is long enough to contain both cases 52 and the cigarettes, therein. It will be noted that the cigarettes project from the case 52 so that when one of the cases is ejected upwardly the exposed ends of the cigarettes may be grasped to facilitate removal of the cigarettes. Obviously the cases 52 may be refilled when desired.

In Figs. 9, 10 and 11 there is shown a smoker's

package 10c embodying the invention and illustrating yet another modified construction. The package 10c comprises an outer tube 70 of relatively stiff material, closed at its bottom end and open at its upper end. Telescoped within the outer tube 70 is an inner tube 71 of softer material which may be filled with loose tobacco or with individual pipe inserts or refills. Attached to the open end of the inner tube 71 is a pouring spout 72 similar to the pouring spout 23, of Figs. 1, 2, 3, and 4. The spout 72 may be attached to the inner tube 71 at one end as indicated at 75. The free end of the tube 72 may be flexed downwardly and inserted within the open end of the tube 70 and between the tubes 70 and 71. Fitted over the open end of tube 70 is a cup shaped cover 77.

Means is provided to release the spout 72 so that it will spring into the shape as shown in Fig. 11. To this end tube 70 is formed adjacent the open end thereof with a longitudinal slot 80. Extending through the slot is a slider 81. Said slider 81 has a head 82 at the outside of the tube and a portion 83 inside of the tube adapted to engage the free end of the spout 72 to eject the same from the tube 70.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A smoker's package comprising an outer container open at one end, an inner container for tobacco or cigarettes, telescoped within the outer container, a cover over the open end of the outer container, said outer container being formed with a slot, means passing through the slot and engaging the inner container to move the same relative to the outer container, and a pouring spout attached to the inner container, the free end of the pouring spout being flexed to engage said outer container in position covering the open end of the inner container.

2. A smoker's package comprising a container open at one end, a pouring spout attached to the open end of said container, said pouring spout being made of flexible normally stiff material whereby the free end thereof may be flexed and engaged with said container, and means on said container to eject the free end of said spout from said container to permit the spout to snap into stiff shape.

3. A smoker's package comprising an outer container open at one end, an inner container for tobacco or cigarettes, telescoped within the outer container, a cover over the open end of the outer container, said outer container being formed with a slot, means passing through the slot and engaging the inner container to move the same relative to the outer container, a pouring spout attached to the inner container, the free end of the pouring spout being flexed to engage said outer container in position covering the open end of the inner container, said spout being made of a flexible, normally stiff material.

4. A smoker's package comprising an outer

tubular container closed at one end and open at the other end, an inner tubular container telescoped within the outer container, a cup shaped member within the outer container frictionally receiving the lower end of the inner container, the outer container being formed with a longitudinal slot, a handle on said cup shaped member passing through said slot, and a spout of flexible, normally stiff material attached at one end to one of said containers, and the free end of said spout being engaged within said outer container and adapted to be released upon ejecting said inner container from said outer container.

5. A smoker's package comprising an outer tubular container closed at one end and open at the other end, an inner tubular container telescoped within the outer container, a cup shaped member within the outer container frictionally receiving the lower end of the inner container, the outer container being formed with a longitudinal slot, a handle on said cup shaped member passing through said slot, a spout of flexible, normally stiff material attached at one end to one of said containers, and the free end of said spout being engaged within said outer container and adapted to be released upon ejecting said inner container from said outer container.

6. A smoker's package comprising an outer tubular container closed at one end and open at the other end, an inner tubular container telescoped within the outer container, a cup shaped member within the outer container frictionally receiving the lower end of the inner container, the outer container being formed with a longitudinal slot, a handle on said cup shaped member passing through said slot, a spout of flexible, normally stiff material attached at one end to one of said containers, the free end of said spout being engaged within said outer container and adapted to be released upon ejecting said inner container from said outer container, a cover on the open end of said outer container, said inner container comprising a plurality of pipe refills, and said inner container being perforated between said refills.

10 15 20 25 7. A smoker's package comprising an outer container open at one end, an inner container for tobacco or cigarettes, telescoped within the outer container, a cover over the open end of the outer container, said outer container being formed with a slot, means passing through the slot and engaging the inner container to move the same relative to the outer container, and a pouring spout attached to the inner container.

NICK SEVASTOPULOS.
